UNITED STATES PATENT OFFICE.

GEORGE E. THACKRAY, OF WESTMONT BOROUGH, PENNSYLVANIA.

COKE-OVEN CONSTRUCTION.

1,211,502.

Specification of Letters Patent.

Patented Jan. 9, 1917.

Application filed October 28, 1913. Serial No. 797,701.

To all whom it may concern:

Be it known that I, GEORGE E. THACKRAY, a citizen of the United States, residing in Westmont Borough, in the county of Cambria and State of Pennsylvania, have invented certain new and useful Improvements in Coke-Oven Construction; and I do hereby declare the following to be a full, clear, and exact description of the invention, such as will enable others skilled in the art to which it appertains to make and use the same.

My invention relates to coke oven construction, and more especially to that class of coke ovens having long horizontal retort coking, or distilling chambers, with heating flues in the side walls thereof, certain of the objects of my invention being to improve the construction and arrangement of the walls to increase their durability and prevent leakage, and the manner of controlling the flow of the air and gas to and from the heating flues.

Another of the objects of my invention is the manner of constructing expansion joints at the tops and bottoms of the walls of the retort whereby they may expand or contract without injurious effects.

Another object of my invention is the arrangement of introducing the heating gas into distribution pipes of different lengths, whereby the flow of gas may be controlled separately to each length and to each part of the oven flues, as desired, thereby maintaining the proper temperatures in the different parts of the oven.

A further object of my invention relates to the gas burners which are disposed in such a manner that the nozzles are easy of access for inspection or cleaning from the top of the battery, in case they become clogged with dust or fused particles. These gas burners may be made small so they may be removed through the flues from the top of the battery and others inserted, or they may be formed in the base blocks of the heating flues.

In case the gas distribution pipes are arranged side by side horizontally, a recess is formed on the under side of the base block wide enough to extend over the ports of both distribution pipes, and this formation of the burners in the base blocks of the heating flues with a recess wide enough to extend over the ports in both distribution pipes forms another feature of my invention.

Another object of my invention is to gradually decrease the size of the air inlet ports from the ends of the oven to the center whereby a more uniform heat is imparted to the oven, as it will be readily understood that the exposed ends of the ovens, which are subject to outside cooling influences, will require more gas than the center of the oven. As the inlet air ports decrease in size, I may also enlarge the size of each of the heating flues, although I may construct the heating flues of the same size the entire length of the oven.

A still further object of my invention is embodied in the arrangement of the regenerators and the means for controlling the flow of the air and off-gas to and from the heating flues.

One of the particular features of my invention consists in the arrangement of the regenerators which are longitudinally disposed under each coking chamber and divided transversely of their length into four portions, the outer portions being of less length than the inner ones. These regenerators are adapted to receive heat from the off-gases and by reversal of the flow therethrough are then adapted to heat the incoming air. With a given amount of gas delivered to the end sections of my oven by means of the gas distribution pipes and a similar amount of gas delivered to the interior sections of my oven by corresponding gas distribution pipes, the end sections being shorter than the interior sections, it will be seen that a larger amount of heat is provided to the end portions of the oven than to the intermediate portions thereof, and this therefore has a tendency to maintain the heat of the oven uniform, irrespective of the exterior cooling influences which act on the end sections.

In addition to this the inertia of the flow of off-gases when transversing the oven flues, is such that as large as or a larger proportion of these off-gases or heating gases will pass through the end sections of the regenerators, thereby providing an amount of heat sufficient in the end sections to thoroughly heat the incoming air after reversal, and this therefore provides sufficient amount of heated air to said end sections which together with the amount of gas delivered to the corresponding heating flues will maintain the required degree of heat in the end portions of said ovens. In the drawings herein, I have shown the end sections

and intermediate sections of the regenerators and corresponding heating flues of lengths in the ratio of three to four, the end sections of the regenerators serving six pairs of heating flues and the intermediate sections of the regenerators serving eight pairs, although other proportions than this may be used within the scope of my invention.

My invention also consists in the novel constructions, arrangement and combination of parts, substantially as hereinafter described and pointed out in the appended claims.

Having given a general description of my invention, I will now, in order to make it more clear, refer to the accompanying two sheets of drawings forming part of this specification and in which:

Figure 1 is a diagrammatic view of a battery of retort coke ovens, the central part being broken away, showing the manner of arranging and controlling the air and off-gas mains from the battery to the stacks. Fig. 2 is a vertical longitudinal sectional elevation of the coke oven taken on the line II-II of Fig. 3, which is transverse of the battery, showing one form of distribution pipes and gas burners or nozzles. Fig. 3 is a vertical transverse section taken on the line III-III of Fig. 2, this section being taken longitudinally of the battery and transversely of the ovens. Fig. 4 is a vertical transverse sectional elevation of the lower portion of the retort oven and surrounding parts taken on the same line as in Fig. 3, but on an enlarged scale to show the details more clearly and the manner of forming expansion joints at the bases of the retort ovens. Fig. 5 is a vertical sectional elevation longitudinally of the ovens, showing the upper portion of the heating flues taken on the same line as in Fig. 2, but on an enlarged scale to illustrate the details of the portion and the expansion joints at the top of the heating flues. Fig. 6 is a vertical sectional elevation taken longitudinally of the ovens on the line VI-VI of Fig. 4. Fig. 7 is a vertical section longitudinally of the ovens, showing another form of burners and distribution pipes. These distribution pipes are arranged one above the other, the section being taken substantially on the same line as in Fig. 2, but showing the distribution pipes in section. Fig. 8 is a vertical section, transversely of the ovens, taken on the line VIII-VIII of Fig. 7. Fig. 9 is a vertical section taken on the same line as Fig. 8, but showing the distribution pipes arranged side by side horizontally with a recess formed in the under faces of the burner blocks wide enough to extend over the ports or openings of both distribution pipes. Fig. 10 is a vertical longitudinal section of one of the reversing valves, showing the main air and flue connections thereto.

Fig. 11 is a vertical section taken longitudinally of the oven on the line XI-XI of Fig. 9, showing a portion of the end of the shorter outer distribution pipe in section and a part of the longer one, which extends to the intermediate set of heating flues, in elevation. Fig. 12 is a detail section, transversely of the ovens, showing a removable burner or nozzle with the distribution pipes arranged side by side as in Fig. 9.

Referring now to the numerals of reference on the drawings:—1 indicates a battery of coke ovens with stacks 2 and 3 at the ends thereof, which stacks provide draft and carry away the off-gases. Each stack 2 and 3 is divided centrally at its bottom portion by means of a partition wall 4, forming a double chimney flue in the base of each stack, those in stack 2 being designated by the numerals 5 and 6, and in the stack 3 by 7 and 8. These division walls prevent eddies and interference of gas currents and facilitate the draft.

Outer main air and off-gas flues 9 and 10 extend longitudinally under the battery and transversely of the coking chambers, and inner mains 11 and 12 of greater cross sectional area extend longitudinally of the battery under the intermediate portion thereof. These mains 9, 10, 11, and 12 each have their ends projecting beyond the ends of the battery, and over the ends of each pair, namely 9 and 11, and 10 and 12, is mounted a reversing and air inlet valve hood 13, the detailed construction of which is shown in Fig. 10.

As illustrated in Fig. 1, the left hand portions of the mains 9 and 11 are supplied with air through the valve 14 and the left hand ends of the mains 10 and 12 by the valve 15; while the respective ends of these mains at the right hand end of the battery are supplied with air by the valves 16 and 17. These four valves control the flow of air to the heating flues of the battery, and the reversing portions thereof control the direction of the off-gases from the battery to the stacks to which they are connected by means of the off-gas ducts 18, 19, 20, and 21, as shown in Figs. 1 and 10.

An air intake port is formed at the top of each valve casing, as indicated at 22, 23, 24, and 25, each having an adjustable mushroom valve, as shown at 26, 27, 28, and 29. Above the mains 9 and 10 and communicating therewith by means of passages 30, are located a plurality of regenerators 31, which are below the coking chambers. The interior regenerators 32 are of greater length and area than the end regenerators 31, and are located above the mains 11 and 12 and connected thereto by the passages 33. It will be seen that each portion of each regenerator is connected to its main flue by three openings, 30 and 33 respectively, thus

providing a complete distribution of air and off-gases to all parts of the regenerators whereby their surface is fully utilized.

34 indicate the regenerator ports connecting with the tops of the outer regenerators 31, and 35 are similar ports for the regenerators 32. These ports 34 and 35 connect with the lower longitudinal oven flues 36, which are divided at 64 into lengths corresponding to those of the regenerators located beneath them and the retort ovens 37. The lower oven flues 36 communicate with the heating flues 38 by means of horizontal ports 39 on both sides thereof, which ports preferably decrease in size from the ends of the oven toward the center as shown in Figs. 2 and 6.

Referring now more especially to Figs. 2, 3, 4, 5, and 6 of the drawings, the supply of gas which is burned in the heating flues, enters the battery by means of distribution pipes 40 and 41, the pipes 40 being shorter than the pipes 41 and located above the same, both pipes being embedded in the masonry construction below each row of heating flues 38. Below each individual flue 38 is an opening 42 in the distribution pipes 40 or 41 as the case may be, directing the gas to the nozzles or burners 43, which are seated in the floor walls of the heating flues 38.

The ports 39 admit air into the heating flues 38 just above the burners 43 at either side thereof, where it mixes with the gas which then burns and flows upwardly in the heating flues, thereby heating the ovens, thence through the upper openings 44 which are each controlled by a damper 45 and thence into the top horizontal canals 46.

An expansion joint 47 is formed at the top of the division walls of the heating flues, as clearly shown in Fig. 5 and at the base of the retort oven 37, as shown at 48 in Fig. 4. This expansion joint 48 is made by fitting blocks 49 of refractory material loosely into grooves 50 or resting their ends upon the ledges 51.

Referring now to Figs. 7, 8, 9, and 11, gas is received by the distribution pipes 52 and 53 from the supply pipes 54 and 55. These distribution pipes 52 and 53 are constructed of refractory material formed in sections with their ends rabbeted together and provided with holes 56 for admitting the gas to the burners or nozzle bricks 57 which in this case are constructed in the base blocks 58 of the heating flues 38, as shown. The distribution pipe sections are preferably of rectangular outline in cross section and are either built in the wall horizontally, one above the other, as illustrated in Figs. 7 and 8, or side by side, as shown in Figs. 9 and 11, and in the latter case I prefer to form a recess 59 on the under face of the base block 58, wide enough to extend over the holes 56 in either of the pipes 52 or 53. With this

construction the base blocks 49 of the retort oven 37 may be modified by forming them with inclined edges to rest on correspondingly inclined sides of the wall, as shown in Figs. 8 and 9.

The operation of my invention is as follows:—Assuming that the parts are in the positions shown in the drawings, bituminous coal is fed to each retort oven at intervals of time dependent on the coking period, through the openings 60 at the top of the retort. It will be understood that the retort ovens will be charged or discharged at different times, so that the operation of the battery as a whole will be substantially continuous and an approximately constant supply of gas will thereby be generated. The distilled gas for the coal passes upwardly through branch pipes 61 on top of the battery, thence into the conduit 62, and thence through the gas washers, scrubbers, or other apparatus into a gas holder where the supply and pressure is equalized, these appurtenances being no part of this invention and therefore not illustrated herein, and thence into the condenser (not shown). After the gases have been cooled, cleaned, and freed from tar, ammonia, etc., all or a part of the gases are returned to the battery through the distribution pipes, whereby they are supplied to the gas burners or nozzles to heat the ovens and thereby produce coke.

Referring to Figs. 1, 2, 3, and 10 of the drawings, the flow of the air and off-gas is as follows:—Air enters the valve hoods 13 through the intake ports 22, 23, 24, and 25, passes thence into the mains 9 and 10, thence through the passages 30 into the regenerators 31, thence through the regenerator ports 34 to the horizontal air channels 36 thence through the ports 39 into the end groups of heating flues 38, where it unites with the burning gas from the distribution pipes 40 then flows upwardly through openings 44 at the tops of the said heating flues 110 then through the upper horizontal canals 46, thence downwardly through the interior openings 44 into the interior group of heating flues 38, thence through ports 39 into the lower horizontal flue 36, thence through the regenerators 32. The off-gas flows into the regenerators 32 by way of the ports 35, then through the regenerators 32, then through the openings 33 into the mains 11 and 12, then through the valve hoods 13 past the valves therein into the off-gas ducts 18, 19, 20, and 21, as the case may be, and to their respective chimneys 2 and 3, whence it escapes into the air.

It will be understood that the mains 9, 10, 11, and 12 are formed with a partition at the center of the battery, as indicated at 63 in Fig. 1 and are operated from each end of the battery. When it is desired to reverse the flow of the air and off-gases, the valves are 130

4
turned so as to direct the inflowing air into the mains 11 and 12 and discharge the off-gases through the mains 9 and 10, otherwise the operation is substantially the same, although the flow takes place in reverse directions through all passages except the stacks.

Although I have shown and described my improvements in considerable detail, I do not wish to be limited to the exact and specific details shown and described, but may use such substitutions, modifications or equivalents thereof, as are embraced within the scope of my invention, or as pointed out in the claims.

Having thus described my invention, what I claim and desire to secure by Letters Patent is:—

1. The combination with a plurality of horizontal retort coke ovens, of a plurality of regenerators extending longitudinally under each oven, vertical heating flues in the side walls of said ovens, a horizontal channel under each oven connected with each heating flue by a port, the regenerators under the end portions of the oven being of less length than those under the interior portions of said oven, connections between the regenerators and the said horizontal channels, means for supplying heating gas to each of the said vertical flues, and means for supplying air to the regenerators and for reversing the direction of flow through the regenerators and heating flues.

2. A plurality of horizontal retort ovens arranged side by side with vertical heating flues in the side walls thereof, a plurality of regenerators below each oven, a horizontal channel between the regenerators and each oven connected to said regenerators and the heating flues, the regenerators under the end portions of the ovens being of less length than those under the interior portions, means for supplying heating gas to the vertical flues, means for supplying air to the regenerators and means for reversing the direction of flow through said regenerators and heating flues.

3. A horizontal retort coke oven, with vertical heating flues in the side walls thereof, a plurality of regenerators located directly below said coke oven communicating with said heating flues through a horizontal channel located between the tops of the regenerators and the bottom of the oven, a gas supply to the end heating flues of the ovens, a separate gas supply to the interior heating flues of the ovens, the regenerators below and directly connected to each set of heating flues being separate, whereby the heating of said oven may be equalized.

4. In a retort coke oven having vertical side walls provided with groups of vertical heating flues, regenerators substantially as long as each of said groups under each

oven, a burner at the lower end of each heating flue, means for admitting air into the heating flues on either side of each burner, and a damper for controlling the openings at the upper end of each heating flue.

5. In a retort coke oven having vertical side walls provided with groups of vertical heating flues, regenerators substantially as long as each group of vertical heating flues under each oven, a burner at the lower end of each heating flue, a plurality of distribution pipes of different lengths connecting with said burners and adapted to furnish gas to the burners in groups, and means for admitting air to the vertical heating flues above the burners on opposite sides thereof.

6. In a retort coke oven having vertical side walls provided with a plurality of vertical heating flues, a burner at the lower end of each heating flue, distribution pipes of different lengths beneath said vertical heating flues adapted to furnish gas to the burners in groups, one set of distribution pipes controlling the flow of gas to the groups of vertical heating flues at the ends of the oven, another set of distribution pipes for controlling the flow of gas to groups of vertical heating flues for the intermediate portion of the oven, and means for admitting air to the vertical heating flues above the burners through the opposite side walls.

7. In a retort coke oven having vertical side walls provided with a plurality of vertical heating flues, a burner at the lower end of each heating flue, distribution pipes of different lengths beneath said vertical heating flues adapted to supply gas to the burners in groups, one set of distribution pipes controlling the flow of gas to the groups of vertical heating flues at the ends of the oven whereby the burning gas flows intermittently from the ends of the oven inwardly and downwardly, discharging through groups of intermediate flues, another set of distribution pipes adapted to control the flow of gas to groups of vertical heating flues of the intermediate portion of the oven, whereby the burning gas flows intermittently from the intermediate portion of the oven outwardly and downwardly, discharging through the groups of end flues, and means for admitting air to the vertical heating flues above the burners through the opposite side walls.

8. In a retort coke oven having vertical side walls provided with a plurality of vertical heating flues, a burner at the lower end of each heating flue, openings adapted to admit air to the vertical heating flues above the burners through the opposite side walls, distribution pipes of different lengths beneath said vertical heating flues for supplying gas to the burners in groups, one set of distribution pipes controlling the flow of gas to the groups of vertical heating flues

- at the ends of the oven, whereby the burning gas flows intermittently from the ends of the oven inwardly and downwardly, discharging through groups of intermediate 5 flues, another set of distribution pipes for controlling the flow of gas to groups of vertical heating flues for the intermediate portion of the oven, whereby the burning gas flows intermittently from the intermediate 10 portion of the oven outwardly and downwardly, discharging through the groups of end flues, and means for reversing the direction of the gases in the groups of heating flues to produce said intermittent flows.
- 15 9. In a retort coke oven having vertical side walls provided with a plurality of vertical heating flues, a burner at the lower end of each heating flue, said vertical heating flues being arranged in groups on each side 20 of a central transverse wall, regenerators of length corresponding to each group, distribution pipes adapted to control the flow of gas to each group of vertical heating flues, horizontal flues adapted to admit air to each 25 group of vertical heating flues and means for reversing the flow of air and gas in the vertical heating flues.
10. In a retort coke oven having vertical side walls provided with a plurality of vertical heating flues, a burner at the lower end 30 of each heating flue, said vertical heating flues being arranged in two groups of unequal length, the outside ones being the shorter, on each side of a central transverse wall, distribution pipes adapted to control the flow of gas to each end group of vertical heating flues whereby the gas flows inwardly, distribution pipes adapted to control the flow of gas to each intermediate 35 40 group of vertical heating flues whereby the gas flows outwardly, horizontal flues adapted to admit air to and communicating with regenerators substantially as long as each
- group of vertical heating flues, and means for reversing the flow of air and gas in the 45 vertical heating flues.
11. In a retort coke oven having vertical side walls provided with a plurality of vertical heating flues, a burner at the lower end of each heating flue, said vertical heating 50 flues being arranged in two groups on each side of a central transverse wall, distribution pipes adapted to control the flow of gas to each end group of vertical heating flues whereby the gas flows inwardly, distribution 55 pipes adapted to control the flow of gas to each intermediate group of vertical heating flues whereby the gas flows outwardly toward the ends of the oven, horizontal ports connected to the regenerators and decreasing 60 in size from the ends to the center of the oven adapted to admit air to each group of vertical heating flues, the outside regenerators being of less length than the intermediate ones, and means for reversing the flow 65 of air and gas in the vertical heating flues.
12. A horizontal coke oven provided with a plurality of vertical heating flues in the side walls thereof, a regenerator extending horizontally below said coke oven divided 70 into four sections, the end sections of said regenerator being shorter than the intermediate sections, gas distribution pipes arranged to supply gas to sections of the oven heating flues corresponding to the sections 75 of the regenerators, means for reversing the direction of flow through said flues and regenerators and means for controlling the supply of gas to said distribution pipes, substantially as described. 80

In testimony whereof I hereto affix my signature in the presence of two witnesses.

GEORGE E. THACKRAY.
